UNITED STATES PATENT OFFICE.

JOHN D. BAILEY AND JOHN M. PHILLIPS, OF HARDAWAY, FLORIDA.

STUMP-PULLER.

1,197,096.

Specification of Letters Patent. Patented Sept. 5, 1916.

Application filed January 8, 1916. Serial No. 71,017.

To all whom it may concern:

Be it known that we, JOHN D. BAILEY and JOHN M. PHILLIPS, citizens of the United States, residing at Hardaway, in the 5 county of Gadsden and State of Florida, have invented certain new and useful Improvements in Stump-Pullers, of which the following is a specification, reference being had to the accompanying drawings.

10 This invention relates to certain improvements in stump pullers and it is an object of the invention to provide a device of this general character having novel and improved means whereby the same may be employed with a maximum of efficiency.

It is also an object of the invention to provide a device of this general character having novel and improved means whereby it may be assembled with convenience and facility, and whereby the various parts thereof are braced or reinforced in such a manner as to render the device capable of effectively standing all strain imposed thereupon.

The invention consists in the details of 25 construction and in the combination and arrangement of the several parts of our improved stump puller whereby certain important advantages are attained and the device is rendered simpler, less expensive and 30 otherwise more convenient and advantageous for use, all as will hereinafter be more fully set forth.

The novel features of the invention will hereinafter be definitely claimed.

35 In order that our invention may be the better understood, we will now proceed to describe the same with reference to the accompanying drawing, wherein—

Figure 1 is a view in top plan of a stump 40 puller constructed in accordance with an embodiment of our invention, the supporting frame being shown in fragment and the operating means being omitted; Fig. 2 is a sectional view taken substantially on the line 45 2—2 of Fig. 1; Fig. 3 is an enlarged transverse sectional view taken through one of the braces as herein embodied.

As disclosed in the accompanying drawing, F denotes a frame of predetermined dimensions and configuration having secured 50 adjacent an end thereof a spider S, said spider including a central bearing or hub 1 from the lower portion of which radiate the arms 2, preferably four in number, and 55 of such a length as to overlie the side beams of the frame F and secured thereto through

the medium of the bolts 3 in a manner which will hereinafter be more particularly set forth. The central bearing or hub 1 together with the arms 2 have integrally 60 formed therewith the upstanding webs or ribs 4, whereby it will be perceived that the spider S possesses a maximum of strength.

The central bearing or hub 1 has rotatably mounted therein the lower end portion of the 65 vertically disposed shaft 5, to the intermediate portion of which is affixed the drum or windlass 6 to which is operatively engaged the flexible member 7 adapted to be suitably engaged with the stump to be extracted, and 70 which is also adapted to be wound around the drum or windlass 6 upon requisite axial rotation being imparted to the shaft 5.

The upper portion of the shaft 5 is disposed through a bearing 8 having radiating 75 therefrom the downwardly inclined lugs or arms 9, as indicated by dotted lines in Fig. 2, and to which are secured, as indicated at 10, the brace members 11, the lower extremities of which are anchored to the outer extremities of the arms 2 through the medium of the bolts 3 hereinbefore referred to. As herein embodied, each of the braces 11 comprises two U beams 12 coacting in a manner which is believed to be self-evident, and the lower 80 end portion of each of the outer beams 12 has welded or otherwise secured thereto the blocks 14 through which the bolts 3, hereinbefore referred to, are directed, and affording a shoulder 15 with which coacts the 85 clamping nut or bur 16 threaded upon the bolt 3, as is believed to be clearly illustrated in Fig. 2.

The shaft 5 is of such a length as to extend above the upper bearing 8 and to said 90 upper portion of the shaft 5 is keyed the pulley P of predetermined dimensions and preferably consisting of two sections 17 having their adjacent peripheral extremities provided with the inturned lugs 18 through 100 which the conventional clamping members 19 are directed. It is also to be noted that the sections of the hub 20 are provided with the oppositely directed extensions 21 through 105 which the conventional clamping means 22 are disposed.

The rim of the pulley P is provided with an opening 23 through which is directed the flexible member 24, one end of which being secured as at 25 to a spoke 26 of the pulley 110 P, while the opposite extremity of the flexible member 24 is adapted to be operatively

engaged with a suitable source of power and preferably a motor (not shown) mounted upon the frame F. In practice we have found a Lidgerwood double drum engine to be particularly desirable for use in connection with our invention.

As herein embodied, it is to be observed that the flexible member 24 is disposed around a guide pulley 27 rotatably supported by the frame F, whereby the flexible member 24 may be properly directed to the source of power and so that a maximum of pull or strain may be imposed upon the pulley P.

From the foregoing description, it is thought to be obvious that a stump puller constructed in accordance with our invention is of an extremely simple and comparatively inexpensive nature and is particularly well adapted for use by reason of the convenience and facility with which it may be assembled, and it will also be obvious that our invention is susceptible of some change and modification without material departure from the principles and spirit thereof and for this reason we do not wish to be understood as limiting ourselves to the precise arrangement and formation of the several parts

herein shown in carrying out our invention in practice.

We claim:

A stump puller comprising a frame, a spider secured to the frame and including a central bearing and arms radiating from the bearing, an upstanding shaft mounted within the bearing, a drum fixed to the shaft, a second bearing for the shaft arranged above the drum, brace members interposed between the second bearing and the arms of the spider, the upper ends of the brace members being provided with longitudinally disposed recesses, a pulley fixed to the shaft above the second named bearing, said second named bearing being provided with outstanding lugs extending within the recesses of the brace members, and means for securing the brace members and the lugs one to the other.

In testimony whereof we hereunto affix our signatures in the presence of two witnesses.

JOHN D. BAILEY.
JOHN M. PHILLIPS.
